SECURITY ALARM SYSTEM CONTROL MODULE

Thomas J. Holce, Portland, Oreg., assignor to Kentrox
Industries, Inc., Portland, Oreg.

Filed May 11, 1971, Ser. No. 142,427

Term of patent 14 years

Int. Cl. D29—99

U.S. Cl. D72—1 R

FIG. 1

FIG. 2

FIG. 3

FIG. 4

FIG. 5

FIG. 1 is a plan view of a security alarm system control module showing my new design.

FIG. 2 is a front elevation as viewed from the bottom in FIG. 1.

FIG. 3 is a bottom view as viewed from the bottom in FIG. 2.

FIG. 4 is a rear view as viewed from the top in FIG. 1.

FIG. 5 is a side elevation as viewed from the left in FIG. 2.

I claim:

The ornamental design for a security alarm system control module, as shown.
